UNITED STATES PATENT OFFICE.

PERRY BROWN, OF CORAOPOLIS, PENNSYLVANIA.

DRAFT-RIGGING.

1,156,881.

Specification of Letters Patent.

Patented Oct. 19, 1915.

Application filed October 2, 1912, Serial No. 723,521. Renewed October 8, 1914. Serial No. 865,777.

To all whom it may concern:

Be it known that I, PERRY BROWN, a citizen of the United States, and a resident of Coraopolis, in the county of Allegheny and State of Pennsylvania, have invented certain new and useful Improvements in Draft-Rigging, of which the following is a specification.

This invention relates to improvements in draft riggings and more particularly to that type of rigging in which there are a series of flat springs to absorb the shock.

The invention consists in the rigging shown in its preferred embodiment in the accompanying drawings and as hereinafter more particularly described and then pointed out in the claims at the end hereof.

In the accompanying drawings which it will be understood represent the preferable though not the only embodiment of my invention: Figure 1 is a perspective view of part of the under framing of a railway car having my invention applied thereto. Fig. 2 is a detail sectional view through one portion of the face or striking plate. Fig. 3 is a horizontal longitudinal section of the parts shown in Fig. 1. Fig. 4 is a vertical longitudinal section. Fig. 5 is a horizontal section taken through the spring plates. Fig. 6 is a perspective view of the socket by which the shank of the draw bar is connected to the rigging. Fig. 7 is a perspective view of one of the housings for the ends of the spring plates.

Referring now to the details of the drawings by numerals: 1 and 2 designate the ordinary channeled sills, such as are now in common use, between which the draft rigging is located. To the front end of the said sills is connected the usual end sill 4 having a face or striking plate 6 riveted thereto, this plate having vertical walls 8 and 10 between which is left a space which I prefer to have equal to the space between the longitudinal sills 1 and 2. The shank 12 of the draw bar is inserted through the opening between said vertical walls 8 and 10 and its rear end is secured to the draft rigging in a manner to be hereinafter described. The lower portions of each of the vertical walls 8 and 10 of the face or striking plate 6 are provided with slots 16 through which is passed a horizontal key or bar 18. This bar 18 serves as a support or carry iron for the draw bar. In order to maintain the draw bar centrally in position on said hori-

zontal bar or key 18, I prefer to employ two fillers 20 and 22 provided on their sides with hooked extensions 23. Said extensions are inserted through the openings 16 before the horizontal key or bar is placed in position, and said key or bar therefore not only serves as a carry iron for the draw bar but it also serves to hold the fillers 20 and 22 in position. The fillers as well as the vertical walls 65 have recesses 24 and 26 therein which form housings for springs 28 and 30, the springs passing around stems 32 and 34 of the centering plungers 38 and 40; cotters 42 being employed to hold the stems of the plungers 70 in position. It follows from the construction just described that the draw bar may be moved from side to side as occasion requires and when side pressure thereon is released, the draw bar will be returned to its central 75 position by means of the spring actuated plungers 38 and 40.

The shank 12 of the coupler which, as illustrated in Fig. 3, has the usual slot 48 therein, is adapted to fit into a socket 50 formed within the front end of a spring supporting block 52, the forward ends of said socket having slots 54 and 56 through which may be passed a horizontal key or bar 58, which key or bar also passes through slots 60 and 62 in the longitudinal sills 1 and 2, said slots 60 and 62 being large enough to permit movement of the key or bar 58 therein as the draw bar is moved in either direction. The shank 12 of the draw bar, as commonly formed, is provided with two horizontal ribs 64 and 66 and the socket 50 is provided with two integral horizontal members 68 and 70 which are so located that after the shank of the draw bar is inserted in the socket, it may be moved upwardly so that the rib 64 will be behind the horizontal member 68 as illustrated in Fig. 4. At this time, a plate 72 may be inserted through the opening 74 until it is under the recess 76 (see Fig. 6) when the said plate 72 may be moved upward so that it forms an abutment for the under horizontal rib 66 of the shank of the draw bar. Then the assembler may place a second plate 78 under the plate 72 to hold the latter in position, said plate 78 having a lug 80 projecting therefrom through which a cotter 82 is passed to hold the same in position. It follows from this construction that if it is not desired to use the horizontal key or bar 58, the shank of the draw bar is effectually locked to the

spring supporting block 52, the horizontal member 68 of the socket and the movable plate 72 receiving all of the load upon a pull, the plate 72 being located within the recesses 76 shown in Fig. 6 and therefore relieving the plate 78 from any of the load, said plate 78 merely having to support the slight weight resting upon it.

The spring receiving block 52 is preferably a one piece casting and, as illustrated in Fig. 3, has a rectangular opening 81 therein for the purpose of receiving and supporting the spring plates 83. These plates are of the character shown in my Patent No. 1,005,100, granted October 3, 1911, and they therefore need no further description here. The only difference between the plates of the present invention and those of my aforesaid patent is that the plates are made longer and 20 extend through openings cut in the longitudinal sills.

In order to receive the ends of the spring plates 82 and form proper housings therefor, and also to form means for rigidly holding the ends so that the spring plates may be sprung in their centers while held at their ends, I employ pockets or housings 86 and 88 which are riveted or otherwise firmly secured to the outside walls of the 30 channel irons, between the channels thereof, as indicated in the drawings. These pockets 86 and 88 are preferably castings and if desired they may be extended to form reinforcements 90 and 92 through slots 94 and 96 of which may be passed the horizontal key or bar 58 for supporting the shank of the bar. The pockets 86 and 88 have dove-tail openings 100 therein, as indicated in Figs. 1 and 7, through which openings 40 are passed dove-tail keys 102, 104 which are secured in position by having cotters 106 passed through them and through ears 108 cast on the outside walls of the pockets 86 and 88. The construction is such that when 45 the parts are assembled, the dove-tail keys 102, 104 may be removed and the spring plates 82 inserted through the openings 100 and after they are all in position, said openings may be closed by the dove-tail keys 102, 50 104. It follows that should any of the springs be broken or need replacing, one of the keys 102, 104 may be removed and the broken or damaged spring plate removed through the opening and a new one replaced.

It is believed the operation of my rigging will be readily understood by those familiar

with these devices and hence no description thereof is needed.

While I have described and illustrated the 60 preferable embodiment of my invention, it will be manifest that changes may be made therein without departing from the spirit of the invention, the scope of which is set forth by the appended claims. 65

What I claim as my invention is:

1. In a draft mechanism and in combination with longitudinal sills of a car having openings therein, spring plates having their ends passing through the openings in said 70 longitudinal sills, and pockets secured to said sills and projecting outwardly therefrom for receiving and inclosing the vertical sides and ends of the projecting portions of said spring plates. 75

2. In a draft mechanism and in combination with longitudinal sills of a car having openings therein, spring plates having their ends passing through the openings in said 80 longitudinal sills, and pockets secured to said sills and projecting therefrom for receiving and inclosing the vertical sides and ends of the projecting portions of said spring plates, said pockets having an opening through which the spring plates may be 85 inserted.

3. In draft mechanism and in combination with longitudinal sills of a car having openings therein, spring plates having their ends 90 passing through the openings in said longitudinal sills, and integral pockets secured to the exterior faces of said sills for receiving the projecting portions of said spring plates, said pockets forming a complete 95 housing for the projecting ends of said plates.

4. In draft mechanism and in combination with the longitudinal sills of a car having openings therein, spring plates having their ends 100 passing through the openings in said longitudinal sills, pockets secured to the exterior faces of said sills for receiving the projecting portions of said spring plates, one of said pockets having a dove-tailed slot 105 therein through which the spring plates may be inserted, and a key fitting said dove-tailed slot and closing the opening.

In testimony whereof I affix my signature in presence of two witnesses.

PERRY BROWN.
